UNITED STATES PATENT OFFICE.

WILLIAM H. JARDINE, OF PHILADELPHIA, PENNSYLVANIA.

VENTILATOR.

Application filed November 10, 1923. Serial No. 673,877.

To all whom it may concern:

Be it known that I, WILLIAM H. JARDINE, a citizen of the United States, residing in the city and county of Philadelphia, State 5 of Pennsylvania, have invented a new and useful Ventilator, of which the following is a specification.

My invention consists of an improvement in a ventilator embodying an inlet flue at 10 the base, a closed cap at the top, and an intermediate cap, the latter having in its apex a passage for the exit of air, smoke, etc., from said flue and surrounding bands, through which atmospheric air may ascend, 15 said passage being in communication with said bands thus effectively causing the discharge of air through said passage, the invention consisting also in forming said passage of a vastly less diameter than that of 20 said inlet flue whereby the air from the latter is forcibly ejected through said passage, and an increased draft created in the ventilator.

The invention is satisfactorily illustrated 25 in the accompanying drawing, but the important instrumentalities thereof may be varied, and so it is to be understood that the invention is not limited to the specific details shown and described, as long as they 30 are within the scope of the claim.

Figure 1 represents a top plan view of a 35 ventilator embodying my invention.

Figure 2 represents a central, vertical section on line 2—2 Figure 1.

Figure 3 represents a bottom plan view 40 thereof.

Similar numerals of reference indicate corresponding parts in the figures.

Referring to the drawings.

45 1 designates the base flue of the ventilator, the same being adapted to be connected with a chimney or ventilating shaft. Riveted to or otherwise connected with said shaft and rising therefrom are the braces or standards 2, to whose upper ends is riveted the top conical cap 3 of the device, said cap being of usual construction.

Surrounding said cap is the upper circumferential cylinder or band 4 which is 50 open at the top and bottom and is sustained by the braces 5 which are bolted or otherwise secured thereto, said braces being also bolted or otherwise secured to the standards 2 as at 6.

55 Surrounding the band 4 is the exterior

circumferential cylinder 7 which is open at the top and bottom and secured by the braces 8 to said band 4 and by the braces 9 to the standards 2, it being evident that by these means the cap 3 the band 4 and band 7 are sustained firmly in position.

Within the band 7 about the bottom there-of is the lower circumferential cylinder or band 10 which is open at the top and bottom and is supported by braces 11 to the standards 2, said braces being bolted or otherwise secured to said band and standards, thus firmly sustaining said band 10 in position, it being seen that there is employed a plurality of bands within the exterior band, the air being adapted to pass upwardly through all of the bands and thus there is created a draft in the ventilator.

Intermediate of the bands 4 and 10 is the supplemental conical cap 12 which is riveted 75 or otherwise connected with the braces 9 and standards 2, as at 13 and 14.

The apex of the cap 12 is open forming the passage 15 for the exit of air of an apartment, smoke, fumes, etc., that may 80 enter the flue 1, it being seen that the diameter of said passage is contracted say one half of that of said flue 1, and this causes a forcible draft of air through said passage from the bands 10 and 7, whereby the efficiency of the ventilator is vastly increased.

In order to cause the portions 16 of the standards 2 within the cap 12 to conform to the conical form of the latter said portions are deflected angularly inwardly from the 90 adjacent vertical lengths of said standards 2, as most plainly shown in Figure 2.

It will be seen when the air from an apartment, smoke, etc., enters the flue 1, it rises to and reaches the cap 12 and escapes 95 through the passage 15 when it impinges the underside of the top cap 3 and is deflected laterally therefrom and so enters the band 4 by which it is directed into the atmosphere.

Atmospheric air enters the bands 10 and 7 and reaches the cap 12 when it mingles with the currents from the flue 1 and forcibly discharges them through the passage 15 to the cap 3. Atmospheric air also enters 105 the band 4 and creates forcible suction around the said passage 15 and generally throughout the body of the device whereby effective ventilation is occasioned.

The diameters of the caps are greater than 110

the diameter of the base flue, whereby rain, sleet, etc., is prevented from dropping through the ventilator into said base flue.

Having thus described my invention, what I claim as new and desire to secure by Letters Patent is:—

In a ventilator, a base flue, a top cap, an intermediate cap of a diameter larger than said top cap and having a central passage therethrough, standards inwardly inclined at their middle portions connecting said base

flue and caps, a relatively narrow annular band arranged between said base flue and intermediate cap, a second relatively narrow annular band arranged adjacent said upper cap, a relatively wide band surrounding said first mentioned bands and spaced therefrom, and braces extended from said standards and connected with all of said bands for supporting the latter. ¹⁵

WILLIAM H. JARDINE.
